ABSTRACT

Hinge and alignment hardware assemblies of molded, cast or drawn materials for hinge mounted doors, shutters and panels, particularly in folding door installations; the same having integral mounting means rendering the use of separate fastening devices, such as mounting screws and the like, extraneous, and comprising radially expandable plug portions insertable into socket openings formed in edge or face surfaces of the doors and panels and including means for positively locking the same in operating position. Guide portions on the assemblies align and position the hardware in conjunction with the mounting plug portions and sockets while interlocking detent projections are provided on cooperating hinge members to retain adjacent panels in coplanar alignment.

SHEET 1 OF 2

1
FOLDING DOOR HARDWARE

BACKGROUND OF THE INVENTION

The traditional and time honored system of mounting and fastening face and edge installed hinges on doors and panels has been through the use of plurality of fastening screws. This requires both time and skill for accurate installation. Present day economic factors, such as high labor costs and the lack of skilled workers, have dictated the need for an improved time-saving, high production system for installing door hardware with accuracy. This is particularly true in folding panel, shutter and door installations currently enjoying popular acceptance and widespread usage in the building arts.

With specific reference to folding door installations, hinges and alignment hardware must be securely mounted and accurately positioned to insure proper movement of the panels in operation. Desirably, the hardware is inconspicuously positioned while avoiding excessive gaps between adjacent panels when the doors are in their closed condition. Typically in the past, hinges have been either flush mounted on the back faces of the door panels or edge mounted using butterfly or butt hinges. In both instances plural fastening screw elements are used to fasten the hardware in place. The butt hinge installation is even further compounded by the requirement for costly counter-sinking of the panel edges to avoid an unsightly gap between adjacent panels. In the event that the panels are made of synthetic materials, such as plastic, according to current trends, counter-sinking for butt hinge installation is an impracticality and usually is avoided. In addition, the utilization of fastening screws with plastic materials is not totally satisfactory since there is a marked tendency of the screws to loosen and back-out of the plastic after repeated operations of the doors.

As a consequence of the above and other factors currently recognized in the industry, not the least of which is the high cost of skilled labor, the need has arisen for improved folding door hardware, principally hinges and alignment means, which are adapted to accurate and quick installation both in the factory and in the field. It is to this growing need that the present invention is addressed.

In my prior application, Ser. No. 335,231 filed Feb. 13, 1973, now U.S. Pat. No. 3,813,730, issued June 4, 1974, I have disclosed the features of an improved hinge means made of molded plastic and incorporation novel plug elements for mounting the hinges in the edges of a door or panel by insertion into machined sockets bored into the door edges. The plug elements carry metal anchoring devices for retaining the same in the sockets, thereby to secure the hinges in place. While further reference may be had to the aforesaid prior application for amplifying details of construction as set forth therein, suffice it to say that the anchoring system disclosed therein has proven to be relatively expensive and complex as compared to the improved structure of the present invention.

In brief, among other features, the present invention is directed to improvements over the hinge disclosed in my prior copending application Ser. No. 335,231, now U.S. Pat. No. 3,813,730, issued June 4, 1974, including the provision of a simplified anchor means of improved retention capabilities for face or edge mounting hardware to a door or panel, and unique detent means for

2

holding doors in coplanar condition over a door opening; the hardware being basically of thermoplastic or synthetic material construction which lends itself to low cost, high production and is capable of accurate and positive installation with minimum time and skill.

It is a principal object of this invention to provide improved hinge and alignment hardware assemblies, particularly useful with folding doors, panels, shutters and the like and which assemblies embody novel means for mounting the same to either face or edge portions of the doors and panels with which they are used.

Another important object of this invention is to provide improved hardware assemblies as aforesaid, which are dependable in use and exhibit economies of manufacture and installation.

Another object of this invention is to provide an improved system of unobtrusively attaching hinge and alignment assemblies to panels and doors having machine bored mounting sockets formed in the edges or faces thereof.

A still further object of this invention is to provide improved hinge assemblies for use with lightweight doors and panels, particularly of the folding variety, which embody improved means for maintaining the doors and panels in coplanar condition.

Having thus described the present invention, the above and further objects, feature and advantages thereof will appear from time to time to those of skill in this art from the following detailed description of a preferred embodiment thereof illustrated in the accompanying drawings and setting forth the features of my present invention so as to enable those familiar with this art to make the practice the same.

35 In the drawings:

FIG. 1 is a front elevational view of a folding door or panel installation utilizing the improved hinge and alignment hardware assemblies of my invention;

FIG. 2 is an enlarged plan view of a hinge assembly 40 of this invention edge mounted on a pair of door panels, as taken from vantage line 2-2 of FIG. 1;

FIG. 3 is a cross-sectional view taken substantially at line 3-3 of FIG. 2 and looking in the direction of the arrows thereon;

45 FIG. 4 is perspective view of the hinge assembly illustrated in FIGS. 2 and 3;

FIG. 5 is perspective view of another hinge assembly according to this invention, illustrated in edge mounted condition intermediate the upper and lower ends of a 50 pair of folding panels or doors;

FIG. 6 is a perspective view of one hinge element of the assembly illustrated in FIG. 5;

FIG. 7 is a partial enlarged front elevational view, 55 with parts in section, of an improved door alignment assembly mounted according to this invention;

FIG. 8 is a cross-sectional view taken substantially from vantage line 8-8 of FIG. 7;

FIG. 9 is an exploded perspective view showing the 60 elements of the alignment assembly illustrated in FIGS. 7 and 8;

FIG. 10 is another perspective view of one alignment member of the assembly illustrated in FIGS. 7 and 8;

FIG. 11 is a sectional view of a modified face 65 mounted hinge assembly according to this invention; and

FIG. 12 is an elevational view of the face mounted hinge assembly shown in FIG. 11.

DESCRIPTION OF THE PREFERRED
EMBODIMENT

Turning now to the features of the particular embodiment of this invention, which is shown in the accompanying drawings for exemplary purposes, initial attention is directed to FIG. 1. As there shown, a structural wall or partition 15 is provided with a door opening 16 as for example, the entrance to a closet. A typical bi-folding door installation is mounted across opening 16 to close over the same and in the particular case shown comprises four planar door panels 17, 18, 19 and 20. The door panels 17 and 18 are hingedly interconnected as are the door panels 19 and 20 to provide a typical bi-folding door installation which, among other advantages, has the ability of providing substantially full access to the door opening, yet is capable of substantially closing over the same while requiring less space for swinging movements of the panels during the opening and closing operations.

While this invention is particularly concerned with improved features of hinge and alignment hardware useful with doors, panels, shutters, decorative screens and the like, it is especially suited for interconnecting adjacent panels of a bi-fold door installation.

Door opening 16 is bounded by lintil 25 across its top, vertical jamb members 26 and 27 along its lateral sides and a floor sill member 28 across its bottom. In the particular bi-fold door installation shown, a horizontal guide track 29 is attached to the lintil member 25 to provide guiding movements to oppositely moving panels 18 and 19 of the two interconnected pairs thereof, as the same move back and forth across opening 16.

Considering the right hand pair of panels 17 and 18 initially, it will be recognized that panel 17 is supported by pivot members 30 and 31 which are axially aligned and located inwardly of one lateral edge thereof in close parallelism to jamb member 26. Pivot member 30 is usually supported in the track member 29 as shown, while the lower pivot center 31 is normally supported on an angle bracket 32 carried by the floor sill 28 and the jamb member 26. The opposite lateral edge 33 of panel 17 is mounted in spaced parallelism to the adjacent lateral edge 34 of panel 18 by improved hinge assemblies 35, 36 and 37 of this invention while a pivotal guide roller 38 is mounted to the upper edge 39 of panel 18 adjacent the opposite lateral margin 40 thereof for engagement with the track means 29 in a conventional and known fashion. An improved alignment assembly 41 comprising a pair of alignment members 42 and 43 is mounted at the lower adjacent corners of the panels 18 and 19, to maintain such panels coplanar in their closed positions.

While the above description is concerned primarily with the hardware associated with the one pair of panels 17 and 18 in FIG. 1, it will be understood that the left hand pair of panels 19 and 20 of the bi-fold installation illustrated are likewise equipped with top and bottom pivot centers 30, 31, top and bottom hinge assemblies 35 and 37 and an intermediate hinge assembly 36 as well as guide roller means 38 and one member of the alignment assembly 41. For purposes of the present disclosure, the description which follows will concern itself primarily with the hinge and alignment assemblies associated with the two right hand door panels 17 and 18 to avoid unnecessary repetition.

It will be understood from the foregoing brief description that with the panel pairs interhinged for relative swinging movement about the interconnecting hinge assemblies 35, 36 and 37 and pivotal movement about the pivot centers 30, 31, the same are adapted to swing about two axes so as to fold toward one another during opening movements. Conversely, the closing movements of the hinged panels produces a generally coplanar closed relationship therebetween, as illustrated in FIG. 1. In order to assist in the opening and closing movements of the doors, suitable knobs or hand grips 44 are usually provided on the exteriors of the pivotally supported panels 17 and 28, generally near the mid-regions thereof, as shown.

As noted above, a bi-fold door installation of the type illustrated is preferably provided with the alignment assembly 41 composed of the individual members 42 and 43, one thereof being attached to each of the adjacent mid-panels 18 and 19. In operation the alignment assembly 41 serves to align the free edges of the two panels 18 and 19 in coplanar relationship and hold the door panels in proper position at and adjacent the lower ends thereof in cooperation with the roller guide means 38, 38 at the upper edges of such panels, to maintain a desired coplanar relationship therebetween in the closed condition of the door installation. The operating features and advantages, as well as the structural aspects of the alignment assembly 41, will be described in greater detail hereinafter from which the foregoing generalities of operation will be readily recognized.

Turning now to the particulars of the improved hinge assemblies 35 and 37 of this invention, reference is made to FIGS. 2, 3 and 4 of the drawings illustrating an upper or top hinge assembly 35. In this regard it should be appreciated and recognized that the bottom hinge assembly 37 is substantially identical to the upper assembly 35 except that the individual members or elements thereof are inverted and reversably positioned so that a description of a top assembly will suffice for both.

Be that as it may, hinge assembly 35 is made up of two unitary hinge members or elements 50 and 51, each preferably molded from thermoplastic material, such as Nylon, or alternatively cast or drawn from metal.

As shown, a male hinge element 50 has a generally planar body portion 52 of substantially square plan profile and of rectangular cross-section. The bottom surface 53 of the body member 52 constitutes a planar guide surface adapted to abut the adjacent end surface of the door panel on which it is mounted, such as end surface 39 on panel 18. Formed integrally with body portion 52 is a depending cylindrical mounting plug portion 55 for mounting the hinge element in an accurately located mounting socket 56 (see FIG. 3) formed inwardly of the end surface 39 of the door panel. Plug portion 55 is distinguished by a generally tapered axial opening 57 extending centrally therethrough for reception of a tapered locking pin 58. The central opening 57 also openly communicates with the exterior surface 59 of the mounting plug via a slotted aperture 60 which extends radially through the main body portion 52 for the full axial length of the mounting plug. Because of this construction, the walls of the body portion normally contract to close the slot 60 at its lower end. However, insertion of the locking pin 58 in opening 57

radially expands the walls of the plug portion to restore its cylindrical shape and positively lock the latter in the mounting socket 56.

It will further be appreciated from an examination of FIGS. 3 and 4 in particular that the external wall 59 of the mounting plug portion is distinguished by one or more radially projecting ribs 62 and rows of locking bars or teeth 63. In the normal non-expanded or unmounted condition for the mounting plug portion, the same is somewhat tapered in external configuration due to the slotted opening 60 being closed at the lower end thereof as above noted. Thus the plug is readily insertable into the cylindrical socket 56. However, after inserting the plug portion into its socket, driving the pin 58 into opening 57 causes radial expansion of its flexible wall portions to drive the teeth 63, and rib elements 62 into the side walls of the socket, preventing rotational movement of the plug portion in the socket. Also, since the tang portions of teeth 63 are reversely formed and readily penetrate and grip the side walls of the socket 56, ready withdrawal of the mounting plug portion is prevented. In practice it has been found that the utilization of the locking pin and expandable mounting plug portions provides a superior system for retaining hinge assemblies in the door in a secure fashion. This is true for both wood and plastic door materials.

In addition to the mounting plug portion 55, the body 52 of the male hinge element 50 is provided with a depending flange skirt 65 on one margin thereof, preferably along its rearward margin as viewed in FIG. 2. Flange skirt 65 like the body portion 52 is provided with a planar inner face 66 adapted to engage the rearward face 67 of the door 18; face 66 being formed at substantially right angles to the lower guide surface 53 of the body portion. With proper location of the mounting socket 56 in conjunction with the mounting plug portion 55 and the flange wall 65, the male hinge element 50 is accurately and positively located over the door edge in its installed position as illustrated in FIG. 3.

It will be observed that in addition to the flange wall 65, body portion 52 of the hinge element 50 is also provided with an outwardly projecting hub portion 70, formed at one end of flange 65 and located outwardly of body portion 52. Hub portion 70 also projects outwardly of the general plane of the flange wall 65 and is provided with a central axial bore opening for reception of a hinge pin 71 definitive of the hinge axis between the two hinge elements 50 and 51 in assembly. Preferably as illustrated, the axis of the hinge pin 71 is located rearwardly of the rear face 67 of the door panels 18 opposite the gap between the opposing adjacent edges 33 and 34 of the interhinged panels 17 and 18 as best illustrated in FIG. 2. In this latter regard, it will be appreciated that the location of the hinge axis for the hinge elements is determined by the positioning of the mounting socket 56 relative to the edges of panels 17 and 18 and to that end the formation of the mounting sockets preferably is performed with an accurate jig or boring fixture so as to adapt such formation to machine operation, according to currently recognized practice.

In addition to the portions of the male hinge element 50 heretofore described, it will be recognized from FIGS. 2 and 4 in particular, that one lateral edge or margin 73 thereof which, in the mounted position for hinge assembly 35, as illustrated in FIG. 2, lies closest

to door edge 34 and the adjacent female hinge element 51, is configured with an outwardly extending finger portion 75 having a hook element 76 spaced from a recessed margin 77 located at the corner of the body portion 52 opposite the hub portion 70. It further will be noted that the outer margin of the finger portion is substantially coplanar with the hinge axis defined by the pin 71, for reasons which will appear presently.

Turning now to the features of the female hinge element 51, it will be recognized from FIG. 4 that the same includes a planar body portion 80 formed integrally with a depending mounting post portion 81 identical in all respects to the previously described post portion 55. As with the latter, mounting post portion 81 is operatively arranged to receive a tapered pin 58 in opening 57 for radially expanding the same in accordance to the construction previously set forth. Like the male hinge element, female hinge element 51 incorporates an integrally formed flange or skirt wall portion 82 along the rearward marginal edge thereof; the same being formed at right angle relationship to the planar underface 83 of body portion 80 to fit tightly against the rear face 84 of panel member 17 in operation. Further, the skirt wall portion 82 extends rearwardly at its intersection with edge 85 of the body portion to terminate in a cylindrical boss or hub 86 having a central axial opening therethrough and receptive of the hinge pin 71; hub 86 being registeringly disposed over the hub portion 70 of the male hinge element in assembly. In addition, the marginal edge 85 of the body is distinguished by an outwardly projecting finger 87 having a hook element 88 opposite the hub 86 and adjacent an inwardly extending recess 89 provided to receive the finger portion 75 of the male hinge element when the same are in a closed hinge position as illustrated in FIG. 2. It will be recognized that the two hook elements 76 and 88 oppose one another and resiliently interlock in the closed position of the hinge elements; element 88 springing past the stiffer hook portion 76 during the opening and closing operations of the hinge assembly. Once the hook elements are inter-engaged, as illustrated in FIG. 2, the same act as a semi-positive holding detent means for maintaining the associated panels 17 and 18, inter-connected by the hinge assemblies 35 and 37, in planar closed condition against accidental opening. This happenstance occurs, for example, when one set of bifold panels is closed and the other set is closed suddenly to pressurize the air in the closet so that the outward rush of air has a tendency to open the closed panels at their hinge junctions. Heretofore separate hardware assemblies have been employed to prevent this accidental partial opening of the door panels. The present unique system of interlocking hinge elements is believed to be a novel advancement in this art for overcoming this problem.

From the above description of the hinge assembly 35, it will be readily appreciated that with the mounting plug portions inserted into their respective sockets in the top edges of the adjacent door panels 17 and 18, the engagement of the skirt elements or portions 65 and 82 with the rear faces of the two panels 17 and 18 tightly locates and maintains the hinge elements in their proper operating position so that the axis of the hinge pin 71 lies opposite the gap between the opposing adjacent edges 33 and 34 of the panels. Driving the locking pins 58 into the central openings of the mounting plug portions radially expands the latter within their mount-

ing sockets, driving the tangs of tooth elements 63 into the side walls of such sockets to assist in positively anchoring the hinge assembly in position in a most effective manner. Furthermore, it will be noted that the location of the hinge axis at pin 71, rearwardly of the rear faces of panels 17 and 18 and the positioning of the skirtwalls 65 and 82 against the rear faces of such panels substantially hides the hinge assembly leaving only the leading edges of the body portions exposed to view from the door front. In effect, the exposed portions of the top hinge assembly are relatively unobtrusive inasmuch as the same are at the upper ends of the doors and are generally hidden to the normal sight of the viewer.

In a similar fashion, of course, the bottom hinge assembly 37 is mounted at and between bottom end edges of the door panels 17 and 18 to cooperate with the upper hinge assembly in determining the hinging movements of such panels about their respective hinge pins which are coaxially aligned. It further will be understood that by utilizing an accurate jig boring setup, the location of the mounting sockets 56 in the end edges of the doors, is such as to maintain a desirable fixed mounting position for the hinge assemblies to insure a proper, but unsightly gapping or space between adjacent opposing edges 33 and 34 of the two panels 17 and 18. This problem in itself has been much cause for concern in bi-fold door assemblies in the past and of course is successfully confronted and solved by the hinge assembly of this invention.

Turning now to the features of the intermediate hinge assembly 36 mounted substantially medially of the door panels for cooperation with the top and bottom hinge assemblies 35 and 37 (see FIG. 1) attention is initially directed to FIGS. 5 and 6 of the drawings illustrating the details and operational aspects thereof. As shown, assembly 36 comprises a top hinge element 90 and a bottom hinge element 91, which are identical in all respects. For purposes of the present disclosure, the description of the bottom hinge element 91, specifically shown in perspective in FIG. 6, will suffice for both.

Element 91 is formed, as with the hinge assemblies, of cast or drawn metal or molded plastic, and includes a planar body portion 93 substantially rectangular in configuration and of a thickness equal to or just slightly less than a desired gap or spacing between opposing lateral edges 33 and 34 of the panels 17 and 18, for example. Outwardly of the rearward face 94 of the body portion 93 is a mounting plug portion 95, identical in all respects with the mounting plug portions 55 and 81 of the hinge assembly 35 hereinabove described. That is to say, the mounting plug portion 95 is a generally cylindrical molded projection having an elongated axially extending opening 96 receptive of a tapered locking pin 97 and split by an axially extending slot 98 to permit radial flexing or contracting and expanding movements of the plug portion. A plurality of bars or teeth 99 project from the exterior surface of the mounting plug portion as in the previously described construction. It will be noted also that the upper edge of the body portion 93 extends diametrically across the cylindrical formation of the mounting plug portion 95, bisecting the central opening 96 which also partially interrupts the body 93. The outer or left hand end of the body portion 93, as illustrated in FIG. 6, is formed with a cylindrical hub 100 having a central bore opening 101 therethrough for receiving a hinge pin 102 in its as-

sembly with the upper hinge element 90 (see FIG. 5).

As previously noted, the upper hinge element 90 of the intermediate hinge assembly 36 is identical to the lower hinge element 91 just described, being however reversibly positioned from the latter in assembly therewith so that the hub portion 100a thereof is axially superimposed over the hub portion 100 for reception of the hinge pin 102. In assembly with the two door panels 17 and 18, two bored sockets of cylindrical formation are formed inwardly of the door edges 33 and 34, the axes thereof being aligned for coaxially receiving the mounting plug portions 95 and 95a of the two hinge elements. The locking pins 97 are driven into the central openings 96 to tightly lock the hinge elements in operating position so that their hinge axis, defined by pin 102, is coaxially aligned with the hinge pins of the top and bottom hinge assemblies 35 and 37 rearwardly of the back faces of the two panels 17 and 18. It further will be noted that the relatively thin body portions 93a and 93 of the two hinge elements 90 and 91 are disposed in the gap or space between the opposing door edges 33 and 34, with the body portion 93a of the upper hinge element 90 swinging registeringly over the body portion 93 of the lower hinge element in the closed position of the door panels.

While the edge-mounted intermediate hinge assembly 36 hereinabove described is preferred in most instances because of its relatively unobtrusive appearance when the door panels are closed, it is nevertheless quite apparent when the door panels are in their open position inasmuch as the lateral edges 33 and 34 of the adjacent panels 17 and 18 are then in full view to the onlooker.

As an alternative, a face mounted intermediate hinge assembly 106, of FIGS. 11 and 12, may be utilized. From an examination of those figures, it will be seen that the modified face-mounted assembly 106 comprises male and female hinge elements 107 and 108, respectively. As shown best in FIG. 12, the male element 107 has a generally planar body portion 109 of substantially rectangular profile with a medially located projection 110 at one end thereof and comprising a cylindrical hub for reception of a hinge pin 111.

Spaced laterally from the hub portion 110 and extending rearwardly of the back face 112 of body portion 109 is a mounting plug portion 113, adapted to fit into a bored socket 114 formed inwardly of the face 67 of door panel 18, for example. It will be noted that the exterior of plug portion 113 is generally cylindrical and provided with rows of projecting teeth 115. A slot 116 splits the body of the plug portion and an axially extending central opening 117 receives a locking pin 118, as in the mounting plug portions previously described hereinabove. It is to be noted, however, that the axially extent of the plug portion 113 is somewhat foreshortened from that described in association with the top and bottom hinge assemblies 35 and 37 and the intermediate assembly 36. Therefore, the mounting sockets 114 therefor are commensurately foreshortened. Be that as it may, the operation of the mounting plug portion and the locking pin 118 therefor is identical to that described hereinabove.

The female hinge element 108 is formed substantially identical to that of the male element 107 with the exception that the body portion 120 thereof is formed with a pair of spaced hub portions 121 and 122 at the upper and lower corners of one marginal edge 123

thereof; the spacing between the portions 121 and 122 being such as to accommodate the linear extent of the hub portion 110 on the male hinge element 107. Thus, in assembly hub portion 110 of the male hinge element is interfitted between the separated hub portions 121 and 122 of the female hinge element for reception of the hinge pin 111 therethrough. Again, it will be noted that the hinge pin 111 is disposed opposite the gap between opposing edges 33 and 34 of the adjacent door panels 17 and 18, for example, with such location of the hinge axis being determined by the location of the mounting sockets 114 which preferably are formed by machine in a boring jig for accuracy of alignment.

It will be appreciated that the face mounted intermediate hinge assembly 106 is a ready substitute for the edge-mounted intermediate hinge assembly 36 of FIG. 5 and is the full operational equivalent thereof comprising the same concept and mode of attaching the same to the door panels, via the mounting plug portions and locking pins.

As mentioned hereinbefore, in addition to the hinge assemblies of this invention, the same comprises an alignment assembly which is illustrated best in FIGS. 7 through 10 of the drawings. It will be recalled that the alignment assembly 41 is typically disposed between the lower corners of adjacent door panels of opposing pairs in a bi-fold door installation, such as panels 18 and 19 illustrated in FIG. 1. Assembly 41 serves to align adjacently opposing panels in coplanar condition when the doors are closed. A better understanding of the functioning and structure of the alignment assembly 41 will be gained by initial examination of FIGS. 9 and 10 of the drawings.

As illustrated in FIG. 9, the right hand alignment member 42 of assembly 41 comprises a planar body portion 125 having a mounting plug portion 126 projecting upwardly of the upper face thereof for reception in a mounting socket 127 formed inwardly of the bottom edge 128 of the right hand door panel 18 in the four door panel installation illustrated in FIG. 1. The mounting portion 126 is split, has externally projecting teeth and receives a mounting or locking pin 130 through a central axially opening 131 therein, all in the manner of that described previously in association with the hinge assemblies 35 and 36, for example.

Projecting outwardly of the rearward margin of body portion 125 is an upwardly extending right-angularly disposed wall or flange 132 having a planar face adapted to closely hug and fit against the rearward face of the door panel 18, in the same manner as the wall portions 65 and 82 associated with the top and bottom hinge assemblies 35 and 37 (see FIG. 8). Wall portion 132 is formed integrally with a lateral extending coplanar narrowed arm portion 133 which is aligned with the upper edge of the wall portion 132 and extends a distance sufficient to bridge the gap 135 between the adjacently opposed edges 40 and 40a of the door panels 18 and 19 in operation (see FIG. 8). The outer end of the arm portion 133 is angled rearwardly at substantially 45° to provide a guide finger portion 136. This finger portion is adapted to resiliently engage the rear corner edge of the left hand panel 19 or that is, the intersection of face 137 and the edge 40a thereof to guide the panel 19 forwardly during its closing movements so as to engage the rearward face 137 thereof with the inside face 138 of the arm portion 133 when the doors are closed. Due to the fact that the material from which the

guide element 42 is fashioned preferably is a thermoplastic material, such as Nylon, it has relatively good flexibility. As a consequence, arm 133 is slightly flexed rearwardly when engaged by the face 137 of panel 19, closely hugging the same and keeping panel 19 aligned nicely with the rear face of panel 18, slightly flexed rearwardly when engaged.

From a brief examination of FIG. 10, it will be appreciated that the left hand guide member 43 of the assembly 41 is substantially identical to the right hand guide element 42 just described, with the exception that the guiding arm portion 140 thereof, and consequently the projecting angulated finger portion 141 attached thereto, projects outwardly from near the bottom marginal corner of its flange wall 142 substantially where the latter intersects of the main body 143 of member 43. With this arrangement it clears the arm and finger portions 133 and 136 of the right hand guide member 42 when the two doors 18 and 19 are moved toward their closed positions. (See FIGS. 7 and 8).

As with the right hand guide member 42, the left hand member 43 of assembly 41 includes an upwardly projecting split mounting plug portion 145 to enter a bored mounting socket 146 formed inwardly of the bottom edge 147 of the left hand door panel 19 for mounting member 43 in operating position. A locking pin 130, as utilized with the right hand member 42, is employed to securely lock the member 43 to the door panel 19 by radially expanding the split mounting plug portion 45 inside of socket 146.

From the foregoing description, it is believed that those familiar with the art will readily recognize and appreciate the novel departure of the present invention over the prior art and particularly will recognize and appreciate the advantages of the improved mounting system employed whereby the hardware assemblies are readily attachable to the edges or faces of door panels and securely locked in position in mounting sockets therefor. It further is to be recognized that while the present invention has been hereinabove described in association with a preferred embodiment illustrated in the accompanying drawings, such embodiment is readily amenable to change and alteration without departing from the spirit and scope of the disclosed invention, as set out in the following claims:

I claim:

1. For use in guiding and hingedly interconnecting adjacent panels in folding door installation and the like, a hardware assembly comprising: a pair of molded members adapted to be cooperatively mounted on adjacent panels, each said member having a body portion formed with a planar guide surface engagable with a planar surface of a said panel on which its associated said member is mounted, a generally cylindrical radially flexible plug portion formed integrally with said body portion and extending perpendicularly outward of said guide surface thereon, said plug portion having externally projecting barbs and a central axial opening extending therethrough and said body portion; said plug portion being insertable into a cylindrical mounting socket formed inwardly of said planar surface of said panel, and tapered pin means insertable through said body portion into said axial opening for radially expanding said plug portion in said socket thereby to securely set said barbs and anchor its said associated member to said panel.

2. The combination of claim 1 wherein said members are hinge elements formed integrally with interfittable hub portions, and hinge pin means coaxially interconnecting said hub portions, and defining an axis of hinging movement therebetween.

3. The combination of claim 1, and a planar skirt wall formed integrally with said body portion projecting perpendicularly outwardly from one margin thereof, parallel to the axis of said plug portion, said skirt wall having a planar guide face for abutting a second surface of a panel disposed perpendicularly to the said planar surface thereon whereby to align said member on said panel.

4. The combination of claim 3, and a hub portion formed along one margin of said skirt wall, the said hub portions of adjacent members interfitting in operation and having coaxial openings therethrough, and hinge pin means mounted in said coaxial openings and definitive of an axis of hinging movement for said members, which said axis is located outwardly of corresponding said second surfaces of adjacent panels in the mounted position of said assembly thereon.

5. The combination of claim 3, and an elongated guide portion extending angularly outwardly of the said skirt wall, said guide portions of adjacent members of the assembly projecting toward one another and overlapping in the mounted position of the members on adjacent panels, with each said guide portion resiliently engaging the said second surface of an adjacent said panel as the panels move toward coplanar positions thereby to align and hold adjacent said panels in coplanar position.

6. The combination of claim 2 in which the said sockets for said member of the assembly are formed inwardly of corresponding edge surfaces of adjacent panels in selected locations positioning said axis of movement therefor opposite the space between said adjacent panels, and detent means comprising interfitting resilient portions formed integrally with the body portions of said members and along opposing margins thereof for operably retaining said opposing margins adjacently parallel when the said panels attached thereto are in coplanar positions.

7. The combination of claim 1 wherein said pair of members comprise hinge elements, and said mounting socket associated with each thereof is formed in an edge surface of one of said adjacent panels associated therewith, and detent means adapted to resiliently interlock said members comprising cooperating projections interfittingly formed on opposed margins of the body portions thereof and engageable when the panels

attached thereto are coplanar.

8. The combination of claim 2 wherein the socket for each member of said pair is formed inwardly of an end edge surface of a said panel and is located so as to dispose said hub portions opposite the space between opposed lateral edges of said adjacent panels.

9. The combination of claim 2 wherein the sockets for said pair of members are coaxially aligned in opposite lateral edges of adjacent door panels, and the said plug portion of each body portion extends beyond one marginal edge thereof, whereby said body portions are positioned in coplanar adjacency between said plug portions in the coplanar closed position of said panels.

10. The combination of claim 2 wherein the sockets associated with each pair of hinge elements are formed inwardly of corresponding planar face surfaces of said adjacent panels and the axis of hinging movement therebetween lies opposite the gap between opposing marginal side edges of said panels.

11. The combination of claim 1 wherein said plug portions are generally cylindrical and are split longitudinally to permit radial expansion and contraction thereof.

12. For use in hingedly interconnecting adjacent panels in a folding door installation and the like, a hardware assembly comprising: a pair of molded hinge members cooperatively mounted on adjacent panels for movement about a hinge axis therebetween, each said hinge member having a body portion formed with a planar guide surface engageable with a planar surface of one of said panels, a radially expandable and contractable plug portion formed integrally with said body portion and extending perpendicularly outward of said guide surface thereon, said plug portion being axially insertable when in a radially contracted condition into a cylindrical mounting socket therefor formed inwardly of said planar surface on a said panel, means for radially expanding said plug portion to activate means for resisting removal thereof from a said socket thereby to secure its associated said member to said panel, and detent means having cooperating interlocking portions on each of said members and operable to restrain movement thereof about said axis.

13. The combination of claim 12 wherein said means for resisting removal of said plug portion comprises tooth projections on the exterior wall of said plug portion having integral barbs projecting toward the said guide surface to grip the walls of a socket into which a plug portion is inserted.
